UNITED STATES PATENT OFFICE.

RICHARD S. SONLEY, OF ESSEX, CANADA.

DESIGN FOR A COBBLER'S LAST.

SPECIFICATION forming part of Design No. 33,132, dated August 28, 1900.

Application filed May 21, 1900. Serial No. 17,361. Term of patent 14 years.

To all whom it may concern:

Be it known that I, RICHARD S. SONLEY, a subject of the Queen of Great Britain, residing at Essex, in the county of Essex, in the 5 Province of Ontario, Dominion of Canada, have invented a new and original Design for a Cobbler's Last, of which the following is a specification, reference being had to the accompanying drawings, forming a part thereof.

10 Figure 1 is a perspective view showing my new design for last. Fig. 2 is a plan view thereof.

As shown in the drawings, my design consists of the last formed of the two parts A and 15 B, connected by the curved connecting mem-

ber C. The said parts form a last of horse-shoe shape, but with the outer surface substantially flat, as shown.

Having described my invention, what I claim, and desire to secure by Letters Patent, 20 is—

The design for a cobbler's last as herein shown and described.

In testimony whereof I have signed my name to this specification in the presence of 25 two witnesses.

RICHARD S. SONLEY.
